(57) **CLAIM**

The ornamental design for a treadmill console, as shown and described.

DESCRIPTION

FIG. 1 is a front and side perspective view of a treadmill console;

FIG. 2 is a front view of the treadmill console of FIG. 1; FIG. 3 is a side view of the treadmill console of FIG. 1; and, FIG. 4 is a top view of the treadmill console of FIG. 1.

The ornamental design that is claimed is shown in solid lines in the drawings. The broken (dashed) lines shown in the drawings are included for the purpose of illustrating environmental elements only and form no part of the claimed design.
